United States Patent Office.

WILLIAM BROWN, OF MIDDLETOWN, CONNECTICUT, ASSIGNOR TO WILLIAM W. WILCOX AND JOSEPH HALL, JR.

Letters Patent No. 66,296, dated July 2, 1867.

IMPROVED GROMMET.

The Schedule referred to in these Letters Patent and making part of the same.

TO ALL WHOM IT MAY CONCERN:

Be it known that I, WILLIAM BROWN, of Middletown, in the county of Middlesex, and State of Connecticut, have invented an Improved Metallic Grommet for Sails; and I do hereby declare that the following, taken in connection with the drawings which accompany and form part of this specification, is a description of my invention sufficient to enable those skilled in the art to practise it.

The metallic grommet, as usually made, consists of a tube and flange formed integral like a common eyelet, and a ring which fits over the tube, the tube being pushed through the hole made for it in the sail, bringing the flange to a bearing upon one side of the ring, being slipped over the end of the tube upon the opposite side of the sail, so that by turning over the tube upon the ring, all the parts are secured tightly to the sail.

My invention consists in forming the flange and tube or eyelet in two parts, the tube being formed of sheet-brass tubing, and the flange of metal cast upon the tube. This construction admits of the use of a cheap cast metal to form the flange, while the tube is made of better or wrought-metal plate that will admit of ready bending to clinch the eyelet over the ring and to the sail.

The drawings represent a metallic grommet embodying the invention, A representing a section of the same, and B showing its application to a piece of sail. *a* denotes the tube, and *b* the flange, the two constituting the eyelet, as shown at A. The tube is formed tapering, and at its largest end is struck out or flared, as seen at *c*, and upon the outer surface of this flare the flange *b* is cast, as seen in the drawings, the eyelet so formed being applied to the sail, and secured to the same and to the ring *d*, by striking out and down the outer end of the tube in the usual manner, as seen at B. While I prefer to make the tube *a* of sheet brass, the flange or rim *b* may be made of any cheap metal which, when cast, will possess sufficient rigidity for the requirements thereof, and the sheet-tube may be secured to the cast-metal flange by forming the casting with a recess, and stamping a flange from the tube down into such recess in a drop-press.

I claim the improved grommet having a cast-metal flange united, substantially as described, to a sheet-metal tube.

WILLIAM BROWN.
